(57) **CLAIM**

The ornamental design for a drape for a surgical microscope, as shown and described.

DESCRIPTION

FIG. 1 is a front elevational view of a drape for a surgical microscope showing our new design;

FIG. 2 is a rear elevational view thereof;

FIG. 3 is a right side elevational view thereof, a left side elevational view being a mirror image;

FIG. 4 is a top plan view thereof; and

FIG. 5 is a bottom plan view thereof.

FIG. 6 is a partially enlarged front elevational view thereof along the lines 6-6 and 6'-6' of FIG. 1;

FIG. 7 is a partially enlarged rear elevational view thereof; FIG. 8 is a partially enlarged right side elevational view thereof, a left side elevational view being a mirror image; and

FIG. 9 is a partially enlarged top plan view thereof, a bottom plan view thereof being a mirror image.

FIG. 10 is a partially enlarged front, top perspective view thereof at the portion of the lines 10-10 and 10'-10' of FIG. 1; and

FIG. 11 is a partially enlarged front bottom perspective view thereof at the portion of the lines 11-11 and 11'-11' of FIG. 1.

FIG. 12 is a cross sectional perspective view cut along the line 12-12 of FIG. 6 at the portion of the lines 12-12 and 12'-12' of FIG. 1; and,

(Continued)

FIG. 13 is a partially further enlarged cross sectional perspective view of the embodiment of FIG. 1 along the lines 13-13 of FIG. 12.

The even-dash broken lines show portions of the article that form no part of the claimed design. The double dot-dash broken lines show boundaries of the claimed design and form no part thereof.

The article is shown with a symbolic break in its length. The appearance of any portion of the article between the break lines forms no part of the claimed design. The symbolic break lines (i.e., pairs of single dot-dash broken lines) represent a boundary between claimed and unclaimed subject matter and form no part of the claimed design.
